(No Model.)

F. M. MARCY.
MACHINE FOR REPAIRING SPINNING RINGS.

No. 439,883.

Patented Nov. 4, 1890.

UNITED STATES PATENT OFFICE.

FRANK M. MARCY, OF WORCESTER, MASSACHUSETTS.

MACHINE FOR REPAIRING SPINNING-RINGS.

SPECIFICATION forming part of Letters Patent No. 439,883, dated November 4, 1890.

Application filed June 24, 1890. Serial No. 356,593. (No model.)

To all whom it may concern:

Be it known that I, FRANK M. MARCY, a citizen of the United States, and a resident of Worcester, in the county of Worcester and State of Massachusetts, have invented a new and useful Improvement in a Machine for Repairing Spinning-Rings, of which the following is a specification, reference being had to the accompanying drawings, representing a machine embodying my invention, and in which—

Figure 1 represents a sectional view of a spinning-ring. Fig. 2 is a side elevation of a machine for repairing spinning-rings and embodying my invention. Fig. 3 is a vertical sectional view of the same on line X X, Fig. 1. Fig. 4 is an enlarged view of the compressing dies, which are represented in Figs. 4 to 7 as full size. Fig. 5 is a detached view of one of the side dies. Fig. 6 is a sectional view of the same on the line X' X', Fig. 5; and Fig. 7 is a top view of the compressing-dies.

Similar letters refer to similar parts in the different figures.

My invention relates to a mechanism for the purpose of repairing spinning-rings and restoring the flanged track which has become worn by the friction of the traveler and rendered worthless, so that the old and worn ring can be used in a spinning-frame.

A machine embodying my invention is illustrated in the accompanying drawings, although I do not confine myself to the specific details of construction therein shown, as these can be varied in many obvious ways and still embody the essential features of my invention.

Referring to the drawings, A denotes a spinning-ring, shown in sectional view. B denotes the track for the traveler and formed by the flange B' upon the outside and the flange B² upon the inside of the ring, and C denotes the waist between the flanged track B and the base D of the ring.

E denotes the supporting-frame, and F a hanger, in which is journaled the short shaft F', carrying the tight and loose pulleys F² and F³ and the beveled pinion G, engaging the bevel-gear H, having a spline-connection with the vertical spindle I, which is journaled in the bearing I' and supported vertically by

the shoulder I². The upper end of the vertical spindle is provided with the cup-shaped depression I³ to receive the base D of the spinning-ring. The ring A is placed in the recess formed in the end of the vertical spindle and attached to the spindle by means of a set-screw I⁴, causing the rotary motion of the spindle to be imparted to the spinning-ring. Attached to the upper surface of the frame-work E, by means of the foot J, is the post J', in the upper end of which is hinged the arm K, provided with the vertical head K'.

L is a steel block or die sliding in a groove L' in the head K' and capable of being forced downward by a screw L² upon the upper surface of the track A with sufficient pressure to expand the flanged track of the ring laterally, thereby increasing the width of the flanges B' and B². On each side of the head K' are the side dies M M, hinged to the head K' by the pintles M', Fig. 5. The side dies M M are provided with the lips N N, which extend beneath the flanges B' B², so that as the screw L² is screwed down upon the sliding central die L the pressure upon the upper face of the track A will be received by the lips N N, and the flanges B' B² will be compressed between the lips and the end of the central die L. The inner edges of the lips press against the sides of the waist C, and as the flanges B' B² are expanded laterally the edges of the flanges are held by the sides of the side dies at N' and their expansion limited. At the sides of the flanges are the cutting or scraping lips O O, which scrape the edges of the flanges B' B², leaving a smooth and true cylindrical surface upon the edges of the flanges. In like manner the edges of the lips N N serve to scrape against the sides of the waist C and render the surface smooth and cylindrical.

Journaled in the arm K is a pin P, to the ends of which are attached the arms R R, carrying the screws R' R' in their free ends, and as the arms R are dropped in the position shown in the drawings the screws R' are brought into position to bear against the outer sides of the dies M M and compress the sides of the waist C and the edges of the flanges B' B². The arm K and head K' have an angular movement around the pivotal stud K² in

- the post J', and the hole through the arm K is made slightly flaring at each end, as represented by the broken lines K³, in order to allow a slight lateral movement of the head K' to accommodate it to any eccentricity in the movement of the ring A as it is rotated by the spindle I. When a ring has had the flanged track A restored to its proper width and the edges of its flanges rendered smooth and cylindrical, in the manner already described, the screws R' are loosened and the arms R R raised in the position represented by the broken lines R² R², allowing the lower ends of the side dies M M to be thrown out from the head K', and the lips N N disengaged from the flanges B' B², and the head K' to be raised and the finished ring removed and another inserted in its place in the recess I³.
20. The position of the arm K and head K', when raised, is shown in Fig. 1 by the broken lines. The side dies M M are held from any twisting motion which would bring a strain upon the pintles M' by the pins or studs S, which project from the sides of the head K' and enter holes S' in the side dies.
- It will be obvious that instead of rotating the ring A the dies themselves could be rotated and the ring remain at rest, or the specific means shown by which a pressure is exerted upon the central die L to force it down upon the face of the track can be modified; also, the specific means by which a pressure is applied to the side dies can be changed for other and equivalent means, the essential feature of the process and the mechanism required to carry it into effect being the application of pressure to the face of a ring, to expand the flanged track upon which the traveler runs, and at the same time restrain the lateral expansion of the flanges, and to apply to the under side of the flanges a corresponding pressure to counteract the downward pressure of the central die, and relieve the waist of the ring from pressure, and, further, to exert a scraping or rubbing contact of the dies upon the sides of the waist and upon the edges of the flanges B' B², in order to secure a true cylindrical surface. The lower end of the vertical spindle is reduced in size at I⁶, and the bearing is correspondingly reduced in order to allow the pin or spline I⁶ to be withdrawn and the spindle itself raised out of its bearing.
55. What I claim as my invention, and desire to secure by Letters Patent, is—
1. In a machine for repairing spinning-rings, the combination of a ring-holder, substantially as described, by which the ring is held in position to be operated upon, a series of dies arranged to inclose the flanged track of the ring, and screws applied to said dies, whereby pressure is applied to said dies, as and for the purpose set forth.
  65. 2. In a machine for repairing spinning-rings, the combination of a die, by which a pressure is applied to the flanged track of the ring to

expand the same laterally, and a pair of restraining-dies applied to the edges of the flanged track to limit its expansion, substantially as described.

3. In a machine for repairing spinning-rings, the combination of the head K', a die sliding in said head, a screw held in said head, by which pressure is applied to said sliding die, and side dies attached to said head and having lips extending beneath the flanged track of the ring, whereby the pressure applied to the face of the ring is received by said lips, substantially as described.

4. In a machine for repairing spinning-rings, the combination of a die by which a pressure is applied to the face of the flanged track of the ring for the purpose of expanding the same laterally, and supporting dies or lips placed beneath said flanged track to support the same, substantially as described.

5. In a machine for repairing spinning-rings, the combination, with a die by which a pressure is applied to the face of the flanged track of the ring for the purpose of expanding the same, of the dies or lips applied to the waist of the ring, substantially as described.

6. In a machine for repairing spinning-rings, the combination of the head K' and the side dies M M, provided with scraping or cutting lips, whereby the edges of the flanged track are scraped and reduced to a true cylindrical surface, substantially as described.

7. In a machine for repairing spinning-rings, the combination, with a holder for holding the ring to be repaired, said holder having a rotary motion, of the dies L and M M, screws L² and R' R', and head K', substantially as described.

8. In a machine for repairing spinning-rings, the combination of a post J', hinged arm K, and a series of dies carried by said arm and arranged to inclose the flanged track of the ring, and screws whereby pressure is applied to said dies, substantially as described.

9. The combination, with the head K', of the side dies M M, provided with lips extending beneath the flanged track of the ring, said dies being hinged to said head, whereby the dies and their lips are removed from the track of the ring, substantially as described.

10. The combination, with the side dies M M, of the hinged arms R R and screws carried by said arms, whereby a pressure is applied to said dies, substantially as described.

11. The combination, with a series of dies arranged to inclose the flanged track of a spinning-ring, of a vertical rotating spindle, upon the end of which the spinning-ring to be operated upon is held concentrically, substantially as described.

12. The combination, with a series of dies arranged to inclose the flanged track of a spinning-ring, of a vertical spindle by which the ring to be operated upon is held, said spindle being capable of a vertical sliding motion to allow for variations in the thick-

ness of the flanged track or irregularities of movement of the ring, substantially as described.

13. The combination, with a ring-holder in which the ring to be operated upon is held and rotated, of a series of dies by which a pressure is applied to the flanged track of the ring, substantially as described, said dies being capable of a lateral motion to allow for

any eccentricity in the rotation of the ring, to substantially as described.

Dated at Worcester, in the county of Worcester and State of Massachusetts, this 20th day of June, 1890.

FRANK M. MARCY.
